UNITED STATES PATENT OFFICE.

CHARLES A. KOTHE, OF EAST CLEVELAND, OHIO, ASSIGNOR TO THE AMERICAN AUTOMATIC CONNECTOR COMPANY, OF WYOMING, DELAWARE, A CORPORATION OF DELAWARE.

LOCK FOR AUTOMATIC TRAIN-PIPE CONNECTERS.

Application filed March 13, 1922. Serial No. 543,425.

To all whom it may concern:

Be it known that I, CHARLES A. KOTHE, a citizen of the United States, residing at East Cleveland, in the county of Cuyahoga and 5 State of Ohio, have invented a certain new and useful Improvement in a Lock for Automatic Train-Pipe Connecters, of which the following is a full, clear, and exact description, reference being had to the accompanying drawings.

This invention relates to automatic train pipe connecters and is particularly concerned with the provision of means for locking together a pair of connected heads, 15 whereby partial separation is prevented by abnormal pressure in one of the fluid carrying pipes.

The partial separation or gapping of connected heads is due primarily to excess of 20 pressure in the steam line. Ordinarily, a steam pressure of about 45 pounds is carried in the steam line, but sometimes the lines are filled with steam under boiler pressure at about 200 pounds. In cases 25 where the orifices for the air signal pipe, air brake pipe and steam pipe are disposed in a vertical plane with a steam pipe at the bottom, the excessive pressure tends to spread the connected heads at the bottom 30 thus allowing air to escape.

One of the objects of my invention therefore, is the provision of means for preventing the partial gap or separation of connected heads even though the pressure in 35 the steam line is raised above normal operation pressure. To this end, I provide a lock which is automatically operable for locking connecter heads together as soon as a sufficient pressure of steam is admitted 40 into the steam conduit.

Furthermore, my invention contemplates the provision of a lock which is adapted to be released automatically whenever the steam is turned off, whereby the heads may 45 be disconnected while in substantially horizontal position.

Other features include the provision of a lock which may be readily attached to existing train pipe connecters without necessitating extensive changes in the construction thereof. These features will become apparent in the following description,

which pertains to the drawings, and in the appended claims.

In the drawings, Fig. 1 is a side elevation 55 of a pair of automatic connecters showing one of them in section and having a lock embodying my invention; Fig. 2 is an end view of one of the connecter heads shown in Fig. 1; Fig. 3 is a vertical section taken through the connecter, while Fig. 4 is a horizontal section taken on lines 4—4 in Fig. 1 through the connecter head just above the lock.

My invention is adapted for use in various forms of connecters but in the drawings, I have illustrated a form of automatic connecter wherein a spring pressed connecter head 10 is supported by a bracket 11, from a draw bar 12 of the train coupler, and is provided on one side with a projection 13, and on the other side with a recess 14, with orifices 15, 16 and 17 disposed in a vertical plane therebetween. These orifices are adapted to be connected with usual train pipes for the air and steam. In this form of connecter, the head is shown as having a shank 18 which has a sliding and universally movable connection with the bracket 11 and as having a strong compression spring 19 which surrounds the shank and presses the head forwardly of the bracket; the length of the spring being such that when the heads are in coupled position, the springs are normally compressed.

My invention is shown in connection with the connecter heads above described and broadly comprises a lock which is normally held in unlocked position, but is adapted to be controlled by fluid in one of the train pipes for locking the connecter heads together. This lock in its preferred form is adapted to be attached to existing connecter heads, and to be so constructed that coacting projections and recesses may readily be brought together, and released while the heads are in substantially horizontal position. Such a lock may be embodied in a casing 20 which is externally threaded at one end to engage a projection 13, and at the other to receive a cap 21. Both the casing and cap are hollow and are separated by a diaphragm 22 one side of which may be in communication through the conduit 23 with

the steam line 17, and the other side of which engages a latch 24. This latch extends through the casing 20 and is normally held in engagement with the diaphragm by 5 a spring 25; in which position the nose 26 of the latch is within the casing.

Under normal conditions, that is, when the heads are disconnected, the spring holds the latch within the casing. This same condition prevails, however, even when the heads are connected, if the pressure in the fluid line 23 is not sufficient to overcome the force of the spring 25. In this way, the lock may be set to operate at a predetermined pressure merely by varying the strength of the spring.

The preferred means for providing an engagement between the coacting projections and recesses is to provide a shoulder 20 30 in the recess just below the latch. Then when the pressure in the conduit 23 exceeds that exerted by the spring 25, the latch is forced downwardly and in such position that any tendency of the heads to separate is 25 overcome by an engagement between the nose 26 and shoulder 30. As the fluid pressure increases the deflection of the diaphragm is limited by reason of the fact that the latch is so designed, that a shoulder 31 30 engages the casing, thereby limiting further downward movement of the latch.

Since the lock is designed to be operated primarily by steam, provision is made for returning condensation to the steam line, 35 thus preventing the lock from freezing and subsequently bursting the diaphragm. This is satisfactorily obtained by placing the fluid chamber above the train pipe orifice 17 and leading the conduit 23 from the top 40 of the steam connection 32.

My invention is shown on a connector head which is normally urged forward of the bracket 11 by the spring 19; the forward movement being limited by a block 38 which 45 is adapted to engage the rear of the supporting bracket. To hold the head in normal coupling position, I have shown in Fig. 1, a chain 35, one end of which may be anchored as at 36 to the bracket 11, and the other end of which may be adjustably secured as at 37 to the shank of the coupler head. The length of the chain may be adjusted by nuts 39 which are in threaded engagement with the eye-bolts 37.

Assuming that a lock embodying my invention is attached to the connector heads and that two railway cars so equipped are being coupled; then the latches 25 are held within the casing 20 by reason of the springs 60 25. After the heads are automatically coupled and steam is caused to flow through the usual train pipes therefore, the pressure within the chamber above the diaphragm 22 is increased until the force is greater than 65 that exerted by the spring on the other side

of the diaphragm. When this occurs, the nose 26 of the latch is forced downwardly to the position indicated in Fig. 3. Then as the pressure is increased in the steam pipe, any tendency for the heads to spread 70 apart is prevented by the engagement between the latch and shoulder 30. When the steam is turned off, the spring 25 automatically forces the plunger upwardly thereby freeing the latch from the shoulder 75 30 and permitting the heads to be disengaged while held in substantially horizontal position.

From the foregoing description, it will be seen that I have provided a lock which is 80 automatically operable for retaining the connector heads in engagement with each other, and for permitting the normal disengagement while the heads are held in substantially horizontal position. This lock is 85 well adapted for preventing the connected heads from gapping, due to excessive pressure in the steam line, and is so constructed that it may be readily attached to existing connectors. Further advantages include 90 weather conditions, whereby an efficient lock is secured which is capable of universal application.

Having thus described my invention, I 95 claim:

1. In an automatic train pipe connector the combination with a pair of connector heads, each having a projection and a recess, the recess of one head having a shoulder 100 and the projection of the cooperating head having a latch carried thereby and arranged to cooperate with said shoulder, said latch being disposed on the inner side of said projection, a fluid pressure conduit associated 105 with said head, said latch being controlled by the fluid pressure in said conduit.

2. In an automatic train pipe connector, the combination with a pair of connector heads, each having a projection and a recess, each recess having a shoulder and each projection having a latch cooperating with said shoulder for locking said heads together, said latch and shoulder extending in a direction at right angle to the direction of 110 movement of the head during the coupling and uncoupling operation, each head having a fluid carrying conduit, and means whereby fluid from said conduit is caused to 115 actuate said latch for locking purposes.

3. In combination a pair of coacting connector heads, each having a projection on one side and a recess on the other side, each recess having a shoulder disposed in a plane 125 at right angles to the direction of movement of the connectors during the normal coupling and uncoupling operation thereof, a casing carried by each head within the associated projection, a latch member slidably mounted in each casing and adapted to en- 130

gage the shoulder in the cooperating head, a fluid chamber within said casing above the latch member, a diaphragm providing a bottom wall for said chamber and adapted to engage said plunger, a steam conduit carried by each head beneath the chamber of the associated casing, whereby condensa-

tion may flow from the chamber into the steam pipe, and yieldable means associated with each latch for normally holding it out of engagement with the coacting shoulder. 10

In testimony whereof I hereunto affix my signature.

CHARLES A. KOTHE.
